(57) CLAIM

The ornamental design for a baby swaddle attached to a fitted sheet as shown and described.

DESCRIPTION

The FIGURE is a left side perspective view of a baby swaddle attached to a fitted sheet showing my new invention.

The broken lines illustrating a baby, a baby cap, and a mattress below the fitted sheet are for environmental purposes only and form no part of the claimed design. The broken lines illustrating rectangular Velcro patches and an extendible pouch portion in a foot region of the baby swaddle attached to the fitted sheet form no part of the claimed design.
